INVENTOR,

BY WILLIAM A. BRUNO

Dear Sirs
Attorney

UNITED STATES PATENT OFFICE

2,335,041

RIGHT-ANGLE ELECTRIC CONNECTOR

William A. Bruno, Astoria, Long Island, N. Y., assignor to Bruno Patents, Inc., Long Island City, N. Y.

Application August 12, 1942, Serial No. 454,537

1 Claim. (Cl. 174—87)

This invention relates to a right angle connector for electrical conductors, and has particular relation to improved means for joining together electrical conductors which are arranged in directions forming a right angle, and in which one conductor is concentrically located inside of the other.

The main object of this invention is to provide an improved connector for properly connecting tubular outer conductor sections forming a right angle, as well as the inner conductors located inside of said outer conductor sections.

Another object of this invention is to facilitate the proper connection of the inner conductors by soldering or the like while said inner conductors are inserted in the connector assembly.

A further object of the invention is to provide a connector of the above mentioned type, which can be easily manufactured, is of simple construction and is safe and durable in use.

Other objects and the advantages of my invention will appear to those skilled in the art from the following specification and claim and the appended drawing which illustrate, by way of example, several embodiments of the invention, and in which

Figure 1 is a sectional view of a right angle adapter according to my invention;

Figures 2 and 3 are end views of the device shown in Figure 1;

Figure 4 shows an elevation part-sectioned view of a T-shaped adapter, and

Figure 5 is an end view of the connector shown in Figure 4.

Referring now to Figure 1, adapter body 1 consists of a square elbow member having a relatively long first tubular portion 11 and a short second portion 21. Said first tubular portion is provided with a shoulder 2 and is adapted to receive an insulator element 3 having a shoulder 4 lying against shoulder 2. Insulator element 3 has a cylindrical bore provided with a shoulder 5, and is adapted to receive a female contact pin 6, fitting into the bore of insulating part 3. Contact pin 6 is provided with a bore 7 and slots 8, and, as shown in the drawing, has a portion 9 having a slightly tapering surface and bore adapted to receive a male contact pin. The remaining portion 10 of contact pin 6 has a reduced cylindrical shape and is provided with a slot 12, adapted to receive the reduced end portion 13' of a male contact pin 13, the axis of which forms a substantially right angle with the axis of female contact pin 6. A tubular extension part 14, provided with teeth 15, is forced into portion 21

of adapter body 1 in such position that teeth 15 are parallel or at 90° to elbow or adapter body 1. Extension part 14 is provided on its inner surface with a shoulder 16, and is adapted to receive an insulating element 17 fitting into the extension part, and provided with a cylindrical, central bore adapted to receive male contact pin 18, the reduced end portion 18' of which is soldered to female contact pin 6 in slot 12 of the latter. Extension part 14 also carries a coupling nut 19 provided with an inner thread 19', while the outer surface of adapter body 1 has a thread 1' and a serrated end portion 20. Adapter body 1 is further provided with a recess 18, and the recessed portion of tubular part 11 may be punched into a registering recess 18' of insulator 3.

Tubular part 11 is provided with a circular orifice 22, through which soldering can be conveniently done and the adapter body may be filled with an insulating material, if desired. Orifice 22 is then closed by cover 23 which is fastened to the adapter body, i. e. by spinning over the adjacent circular edge of the adapter body.

Tubular portion 11 is adapted to be coupled with a coupling nut and a male contact pin of the type shown at 18 and 18', while male contact pin 13 may be introduced into a suitable connector and coupled with the same by means of coupling nut 19.

The connector shown in Figs. 4 and 5 consists of a T-shaped tubular part, in which the design of the short tubular portion 21 is substantially the same as that shown in Figs. 1-3. Tubular portion 11 is provided in its central part with a circular orifice 22, adapted to be closed by a registering cover 23 in the manner described above, and contains a central female conductor which extends throughout portion 11. This conductor is terminated at both ends by substantially equal parts of the design and construction shown in Fig. 1, and is connected at the center of the T-shaped piece with male contact pin 13 by soldering.

It will be understood that this invention may be carried out in other specific ways than those herein set forth, and the embodiments should be, therefore, considered as illustrative and not restrictive within the spirit of the invention as defined in the appended claim.

I claim:

An electric connector comprising a unitary casing formed of two intersecting tubular members arranged at a substantially right angle, one of said tubular members housing at least one insulator member provided with a shoulder, in a

registering bore having a reduced bore to provide a registering shoulder, one of the tubular members having at the intersection with the other tubular member a circular orifice closed by a cover, said one insulator member having a cylindrical central bore provided with a shoulder, a female electrical contact secured in said central bore, said electrical contact being provided with a terminal end for receiving an electrical contact pin secured in said other tubular member and 10 adapted to make detachable electrical contact with a complementary female electric contact, said one insulator member being restrained from

axial movement by the shoulder provided in said one of the tubular members, and a recess provided in the outer surface of the first insulator member and receiving a registering projection of 5 said one of the tubular members, the other of said tubular members having attached thereto a tubular extension member carrying a coupling nut and carrying a second insulator member and said electrical contact pin which is disposed at a substantially right angle relative to the female electric contact, said electrical contacts being secured in electrical engagement.

WILLIAM A. BRUNO.
